UNITED STATES PATENT OFFICE.

CHARLES H. JOHNSON, OF SALISBURY, NORTH CAROLINA, ASSIGNOR OF ONE-THIRD
TO GEORGE O. LIPE AND ONE-THIRD TO PAUL K. DRY, BOTH OF LANDIS, NORTH
CAROLINA.

DRAWING-ROLL MECHANISM FOR SPINNING-FRAMES.

1,396,122.

Specification of Letters Patent. Patented Nov. 8, 1921.

Application filed May 28, 1921. Serial No. 473,552.

To all whom it may concern:

Be it known that I, CHARLES H. JOHNSON, a citizen of the United States, residing at Salisbury, in the county of Rowan and State 5 of North Carolina, have invented certain new and useful Improvements in Drawing-Roll Mechanism for Spinning-Frames, of which the following is a specification.

This invention relates to spinning frames 10 and has for an object to provide a drawing roll mechanism embodying new and improved features of convenience, reliability and economy.

A further object of the invention is to provide a drawing roll supporting mechanism 15 wherein the bar may be raised bodily from its operative position upon the stand carrying therewith the top rolls without disturbing the tension.

20 A further object of the invention is to provide a drawing roll mechanism wherein the top rolls may be raised together with the bar from their engagement with the bottom rolls without removal from the bar 25 or the relieving of the tension therefrom.

It is well known that in drawing roll mechanisms of the usual and ordinary type the top rolls are carried in a bar hinged to the stand and tension is applied thereto from 30 a weight hinged to the stand by a lever and with connecting means extending upwardly through the structure engaging the bar. To raise the bar and the top rolls therewith it is therefore necessary to disconnect the tension weight or transmission mechanism in 35 many instances to remove the top rolls from the bar to prevent their falling and being damaged when the bar is lifted backwardly. The present invention involves means for 40 maintaining the rolls in their journal bearings in the bar when the bar is raised with the tensioning mechanism employed to maintain the rolls in such position and to restore the exact adjustment of tension when the 45 bar is again returned to operative relation to the stand.

With these and other objects in view the invention comprises certain novel units, parts, elements, combinations, arrangements, 50 mechanical movements and functions, as disclosed in the drawing, together with mechanical equivalents thereof, as will be hereinafter more fully described and claimed.

In the drawing:

Figure 1 is a transverse sectional view 55 through a spinning frame drawing roll mechanism showing the parts in full line in operative position and in dotted lines with the bar turned backwardly.

Fig. 2 is a plan view taken somewhat at 60 an angle, as indicated by the arrow 2 at Fig. 1, said figure also showing line 1-1 as the plane of Fig. 1.

Fig. 3 is an enlarged detailed sectional view taken on line 3-3 of Fig. 2.

Fig. 4 is a perspective view of the tension 65 spring.

Like characters of reference indicate corresponding parts throughout the several 70 views.

The improved drawing roll mechanism, 75 which forms the subject matter of this application, comprises a stand indicated as an entirety at 10 of substantially the usual and ordinary type with the bottom rolls 11 journaled thereon and therein in substantially the usual and ordinary manner.

Pivoted upon the stand 10 is the top bar 12 which in general shape is substantially similar to the usual and ordinary top bar 80 and in which is journaled the top rolls 13, also of substantially the usual and ordinary type.

In the usual top bar of a drawing roll mechanism the top rolls 13 are journaled by 85 simply being set into slots formed in the top bar and rest upon the bottom rolls 11 so that when the top bar is raised the top rolls will fall through the slots. As a part of the present invention, the bottom of these 90 slots are closed, as indicated at 14, whereby the trunnions 15 may engage the bridge piece 14 spanning the lower part of the slots 16 so that when the top bar is raised the trunnions will engage this bridge piece and 95 will raise with the top bar. It will be noted especially from Fig. 3 that this bridge piece 14 is so positioned that when the device is in operative position with the top rolls in engagement with the bottom rolls the trunnions do not engage this bridge piece but are free to float in the slots 16 as in the ordinary construction and that the bridge piece is employed only to prevent the displacement of the top rolls when the bar is raised.

To maintain the bar in operative 100 105

position relative to the stand a latch 17 is employed in the form of a spring which is secured to the stand and extends upwardly between the rolls, both the lower rolls and 5 upper rolls, and hooks over the top of the bar when the bar has been moved downwardly to operative position.

Tension is applied to the top rolls by the use of the saddles 18 and 19 of substantially 10 the usual and ordinary type but instead of applying the tension thereto by means of a weighted lever, as is ordinarily done, a spring 20 is employed having a bifurcated end 21 engaging over the adjusting screw 22, 15 ordinarily found in the saddle construction. To effect a tension upon the spring a bent finger 23 is rigidly attached to the bar at the rear of the bank of rolls under which the spring passes to engage the extremity 20 of an adjusting strut 24. This engagement may be in any approved manner but is preferably produced by providing the spring 20 with a perforation 25 to pass over the threaded extremity 26 of the strut 24 and 25 bear upon the shoulder 27. A keeper in the form of a nut 28 is preferably employed for upon the threaded extremity 26 simply for the purpose of retaining the spring 20 against displacement. The strut 24 is carried by an offset 29, preferably, though not necessarily, cast integral with the bar 12 and is adjusted in any approved manner, as by the nuts 30 and 31. It is obvious that if the strut 24 is raised by the manipulation of 30 the nuts 30 and 31 the tension of the spring 20 will be increased, which will be transmitted to the top rolls 13 through the saddles 18 and 19. A tension so acquired will, of course, be maintained by employing the nuts 35 30 and 31 as lock nuts, each stressing against the other.

It will be obvious, therefore, that the entire combination applied to the top rolls is carried by the bar which may be disengaged 45 by manipulating the latch 17 and lifted and swung backward as, for instance, to the dotted line position shown in Fig. 1, without displacing the top rolls or interrupting the tension so that when the bar is again returned to operative position and forced downwardly and latched the acquired tension will be available.

This arrangement eliminates the necessity of removing all of the top rolls from the 50 bar when the bar is to be raised and maintains all of the parts, including the saddles, in position during such raising and any operation which may be performed upon the lower rolls or to the thread between the rolls.

60 In operation the device will function exactly as an ordinary drawing roll mechanism, as when in operative position the relation and function of the parts do not differ in any particular from the usual and 65 ordinary drawing roll mechanism. The

function of the device is only for the convenience in handling, which includes the raising of the bar and with the convenience is included economy in that it is a saving of time as well as a saving of rolls, as they 70 are not damaged by removal and engagement with extraneous matter, as is usually the case.

I claim:

1. A drawing roll mechanism comprising 75 the combination with a stand and a bar hinged thereto of means to support the top rolls in the bar and means carried wholly by the bar for exerting tension on the rolls.

2. In a drawing roll mechanism the combination with a stand and top bar pivoted 80 thereto of journal bearings formed in the bar proportioned to support the top rolls therein and a top roll tension mechanism carried wholly by the bar.

3. A drawing roll mechanism comprising in combination with a stand and a bar pivoted thereto, a plurality of top rolls, means carried by the bar to support and journal the top rolls and means carried by 90 and movable with the bar for exerting tension upon the top rolls.

4. A drawing roll mechanism comprising the combination with a stand, a top bar pivoted thereto, and top rolls carried by the 95 bar, of journals carried by the bar adapted to maintain the top rolls in journaled relation thereto, a spring carried by the bar and movable therewith, means employing the stress of the spring as a tension upon the top rolls and means to vary the tensional efficiency of the spring.

5. A drawing roll mechanism comprising in combination a stand, a bar and a plurality of top rolls, means carried by the bar for journaling the top rolls irrespective of the underlying structure, tension devices bearing upon the rolls, a spring carried by and movable with the top bar and bearing upon the tension device, and means to vary the tensional efficiency of the spring.

6. A drawing roll mechanism comprising in combination, a stand, a top bar pivoted thereto and a plurality of top rolls, means carried by the top bar to support the top rolls in journaled relation, a tension mechanism engaging the top rolls, a spring carried by and movable with the top bar and bearing upon the tension mechanism, and means to vary the tensional efficiency of the 110 spring.

7. A drawing roll mechanism comprising in combination, a stand, a bar pivoted to the stand, a plurality of top rolls, journals formed in the bar adapted to support the 125 top rolls in journaled relation thereto, a saddle engaging the top rolls, a spring carried by and movable with the bar engaging and bearing upon the saddle, a fulcrum for the lever, a supporting strut for the lever 130

and means to vary the length of the strut to vary the tensional efficiency of the spring.

8. A drawing roll mechanism comprising in combination, a stand, a top bar pivoted to the stand, a plurality of top rolls journaled in the top bar, means carried by and movable with the bar for exerting tension upon the top rolls and a manually operable latch adapted to maintain the bar in operative relation to the stand.

9. A drawing roll mechanism comprising

in combination, a stand, a top bar pivoted to the stand and provided with a plurality of journal bearings, top rolls journaled in the journal bearings, means carried by and movable with the top bar for exerting tension on the top rolls, and a spring latch pivoted to maintain the bar in operative relation to the stand.

In testimony whereof I affix my signature. 20

C. H. JOHNSON.
